US00D620508S

(12) **United States Design Patent**
Jacquet et al.

(10) **Patent No.:** **US D620,508 S**
(45) **Date of Patent:** **** Jul. 27, 2010**

(54) **MACHINE TOOL**

(75) Inventors: **Rémy Jacquet**, Le Locle (CH); **William Kohler**, La Chaux-de-Fonds (CH); **Peter Handlbauer**, Voiron (FR); **Pierre Struzka**, Lausanne (CH); **Patrick Ammon**, Bienne (CH)

(73) Assignees: **Agie Charmilles SA**, Loson (CH); **Charmilles Technology SA**, Meyrin (CH)

(**) Term: **14 Years**

(21) Appl. No.: **29/293,977**

(22) Filed: **Dec. 19, 2007**

(30) **Foreign Application Priority Data**

Jun. 20, 2007 (EM) 000743323

(51) **LOC (9) Cl.** **15-09**

(52) **U.S. Cl.** **D15/122**

(58) **Field of Classification Search** ..... D15/122, D15/124, 127, 128, 130, 131; 29/26 A, 26 R, 29/30, 33 A-33 T, 34 R, 39, 50, 563-566, 29/564.1-564.8; 483/17-57

See application file for complete search history.

(57) **CLAIM**

The ornamental design for a machine tool, as shown and described.

DESCRIPTION

FIG. 1 shows a front view of the design;

FIG. 2 shows a side view of the design from one side;

FIG. 3 shows a side view of the design from the other side;

FIG. 4 shows a top view of the design;

FIG. 5 shows a backside view of the design;

FIG. 6 shows a perspective view of the design; and,

FIG. 7 shows a perspective view of the design with lowered working reservoir.

The broken lines in the drawings depict unclaimed environmental subject matter.
